UNITED STATES PATENT OFFICE.

FREDERIK LECHLER, OF CLEVELAND, OHIO.

CHRISTMAS-TREE CANDLE-HOLDER.

SPECIFICATION forming part of Letters Patent No. 295,182, dated March 18, 1884.

Application filed August 25, 1883. (No model.)

To all whom it may concern:

Be it known that I, FREDERIK LECHLER, of Cleveland, in the county of Cuyahoga and State of Ohio, have invented a new and useful Improvement in Christmas-Tree Candle-Holders, of which the following is a specification.

My invention consists of a device for holding candles on Christmas-trees; and it consists 10 of a clamp for attaching it to a branch or limb, and having a spring of peculiar construction, which serves to press the leaves of the clamp and also hold the candle. This device is capable of being attached to a limb or branch 15 in any position, either horizontal or nearly perpendicular.

In the drawings, Figure 1 is a perspective view of my device as seen attached to a limb. Fig. 2 is a side elevation. Fig. 3 is a vertical 20 section. Fig. 4 is a detached view of the spring and candle-holder.

A A are the two leaves of the clamp. These may be made in the form shown, or other form which taste may dictate. Said leaves are pro-

vided with ears a a near the middle of their 25 sides, through which a pintle, b, passes, forming the joint.

C is a coil-spring embracing said pintle, and having its end extending upward, with one arm bearing against one leaf, while the other 30 arm terminates with a spiral coil, c, forming a socket for holding a candle. The said wire spring and candle-holder are made of one piece of wire, and serve both purposes—that of pressing the clamp and holding the candle. 35

This makes a cheap and simple device for the purpose of attaching candles to the branches of Christmas-trees in any desired position.

Having described my invention, I claim— 40

The combination of the coiled-wire spring and candle-holder C and the leaves A A and pintle b, substantially as and for the purpose specified.

FREDERIK LECHLER.
